DESIGN FOR A DRESS ENSEMBLE

Sabina De Pasquale, New York, N. Y.

Application May 15, 1939, Serial No. 84,987

Term of patent 3½ years

To all whom it may concern:

Be it known that I, Sabina De Pasquale, a citizen of the Kingdom of Italy, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design;

Fig. 2 is a rear view of Fig. 1;

Fig. 3 is a front view of the dress member of the ensemble shown in Fig. 1 and

Fig. 4 is a rear view thereof.

The characteristic feature of my design resides in the combination on the ensemble disclosed of the specific arrangement of tucks around the bottom of the jacket member in association with the embroidered revers and the specific dress section as shown.

I claim:

The ornamental design for a dress ensemble, substantially as shown and described.

SABINA DE PASQUALE.
